(57) **CLAIM**

What is claimed is the ornamental design for a combined bottle and cap, as shown and described.

DESCRIPTION

FIG. 1 is a front elevation view of our new design for a combined bottle and cap;

FIG. 2 is a left side elevation view thereof, a right side elevation view being identical;

FIG. 3 is a top plan view thereof;

FIG. 4 is a rear elevation view thereof; and,

FIG. 5 is a bottom plan view of our new design.

Broken lines showing environmental structure are solely for illustrative purposes and form no part of the claimed design.
